UNITED STATES PATENT OFFICE

2,215,670

ORCHARD AND HOOTHOUSE HEATER

Charles W. Stewart, San Diego, Calif.

Application August 28, 1937, Serial No. 161,475

4 Claims. (Cl. 126—59.5)

My invention relates to a heater for heating orchards, hothouses, or the like, and the objects of my invention are,

First, to provide a heater to be used among the trees in an orchard or among the trees and shrubbery around a hothouse for heating the area around the trees or shrubs to keep them from becoming frosted when there are exceptionally cold short periods;

10 Second, to provide a heater of this class in which various fluids or gases may be burned and the heat distributed therefrom efficiently;

Third, to provide a heater of this class with means in connection therewith for vaporizing the 15 fluid on its passage to the burner;

Fourth, to provide a heater of this class in which a body of refractory material is heated and, therefore, radiates the heat;

Fifth, to provide a novel fuel burner;

20 Sixth, to provide a heater of this class with means for taking care of the waste or sludge from the vaporizing of the fuel in its passage to the burner;

Seventh, to provide a new and novel orchard 25 heater, and

Eighth, to provide an orchard heater of this type which is very simple and economical of construction, easy to operate, efficient in its action, and which will not readily deteriorate or 30 get out of order.

With these and other objects in view as will appear hereinafter, my invention consists of certain novel features of construction, combination, and arrangement of parts and portions as will be 35 hereinafter described in detail and particularly set forth in the appended claims, reference being had to the accompanying drawing and to the characters of reference thereon which form a part of this application in which:

40 Figure 1 is a sectional view of my burner taken from the line 1—1 of Fig. 2 and showing some of the parts and portions in elevation to facilitate the illustration; Fig. 2 is a fragmentary top or plan view of the burner, and Fig. 3 is a sectional view taken from the line 3—3 of Fig. 1.

45 Similar characters of reference refer to similar parts and portions throughout the several views of the drawing.

The leg members 1, 2, and 3, refractory material supporting pan 4, refractory material 5, burner cylinder 6, burner nozzle member 7, fuel distributing nozzle 8, cylinder head 9, plug 10, vaporizing tube 11, and sludge outlet plug 12 50 constitute the principal parts and portions of my orchard and hothouse heater.

The leg members 1, 2, and 3 are preferably made of strip metal and are provided with outward turns 1a and 2a at their lower ends. There are three of these leg members which form a tripod for supporting a burner cylinder 6. This burner cylinder 6 is provided on its outer surface near its upper end with straight lug portions 6a, 6b, and 6c, shown best in Fig. 2 of the drawing, and secured to these lug portions are the upper ends of the leg members 1, 2, and 3 by means of 55 angular bend portions 1b, shown best in Fig. 1 of the drawing. Secured to these leg members 1, 2, and 3 at their inner sides and placed some distance from the lower ends of said leg members, is a refractory material supporting pan 4 10 which is provided with an upwardly turned edge 4a and this edge is turned inwardly at the leg portion, as shown at 4b, so that it assumes the angle of the leg members. This pan 4 is filled with a rounded heaped mass of crushed rock or 15 other suitable refractory material which is adapted to receive the blaze from the burner and spread and distribute the same and the heat therefrom. It will be noted that the cylinder 6 is positioned in a vertical position and mounted 20 in the lower end thereof is a nozzle member 7 which is in the form of a spider with a central opening 7a and outer openings 7b, see Fig. 3, providing for the proper distribution of the flames 25 from the burner cylinder as shown by arrows in Fig. 1 of the drawing. This cylinder 6 is provided with an integral head portion 9 which extends upwardly above the cylinder and across the upper end, said cylinder being open at its upper end on opposite sides of the member 9 at 6d and 6e 30 to admit air to the upper end of the cylinder, which head portion is provided with a fuel conductor 9a therein and between this fuel conductor 9a and the upper end of the cylinder 6 is a nozzle member 8 which is screw threaded in a 35 hole between the upper end of said cylinder and the conductor 9a. This nozzle member 8 is provided with a very small orifice 8a in its lower end which provides for the exit of the fuel and it will be noted this nozzle member extends slightly 40 below the upper end of the cylinder, and also extends upwardly into the conductor 9a some distance as shown best in Fig. 1 of the drawing. Positioned in the head 9, directly above the nozzle 8 is a plug 10 which serves to provide accessibility to the nozzle member 8 for cleaning the same. The cylinder head 9 is provided with an outwardly extending portion 9b which is provided with a bore in its extended end 9c in which 45 is mounted the upper end of the vaporizing tube 50 55

11. It will be noted that this vaporizing tube 11 is positioned so that it receives the blaze and heat reflected from the burner by the refractory material on the pan 4, thus vaporizing the fuel on its way to the burner. This vaporizing tube 11 is positioned on an angle as shown, and is provided at one side with an outwardly extending fuel inlet conductor portion 11a which has a threaded portion 11c for connection with an inlet fuel conductor which may be any suitable conductor, not shown in the drawing. This tube extends downwardly from the inlet portion 11a and the lower portion 11c forms a trap for waste or sludge caused by the vaporization of the fuel and there is provided means for cleaning this waste or sludge, which is a plug 12 which is in the lower end of the member 11c.

The operation of my heater is as follows:

The heaters are placed in the proper position
20 on the ground under the trees in the orchard
and are connected up with a fuel supply by means
of the members 11a and 11b in Fig. 1 of the draw-
ing and it will be here noted that the burner is
adapted to burn gases such as natural gas, butane
25 gas, or liquid gases. The fuel is then forced
through the distributing system, passes through
the inlet 11a, through vaporizer 11, through the
passage in conductor 9a, then downwardly
through the nozzle 8 and there mixing with air
30 entering the upper end of the cylinder 6 and the
mixture passes out through the spider-like burner
nozzle 7 in the form of a blaze which strikes the
refractory material 5 on the rounded upper side
and is reflected outwardly, some of it striking the
35 vaporizing tube 11 and vaporizing the fuel, the
remainder passing outwardly into the tree foliage
and thus heating the area surrounding the trees.

40 Though I have shown and described a particular construction, combination, and arrangement of parts and portions, I do not wish to be limited to this particular construction, combination, and arrangement, but desire to include in the scope of my invention the construction, combination, and arrangement substantially as set forth in the
45 appended claims.

Having thus described my invention what I claim as new and desire to secure by Letters Patent is:

50 1. In an orchard heater of the class described, the combination of a down draft burner including a hollow cylinder positioned on a vertical axis and provided with a spider-like nozzle at its lower end, a small fuel distributing nozzle positioned on a vertical axis centrally in the upper end and
55 provided with air inlet openings on opposite sides of said nozzle, provided with an enclosed fuel inlet communicating with the upper end of said fuel distributing nozzle, a vaporizing tube communicating with said enclosed fuel inlet at its
60 upper end and extending downwardly and provided with a fuel inlet at one side of said vaporizing tube, a sludge trap below said fuel inlet in integral connection with said vaporizing tube, and a plurality of leg members secured at their
65 upper ends to said cylindrical burner member at its side walls and extending downwardly in an angular position.

2. In an orchard heater of the class described, the combination of a down draft burner including a hollow cylinder positioned on a vertical axis and provided with a spider-like nozzle at its lower end, a small fuel distributing nozzle positioned on a vertical axis centrally in its upper end and provided with air inlet openings on opposite sides of said nozzle, provided with an enclosed fuel inlet communicating with the upper end of said fuel distributing nozzle, a vaporizing tube communicating with said enclosed fuel inlet at its upper end and extending downwardly and provided with a fuel inlet at one side of said vaporizing tube, a sludge trap below said fuel inlet in integral connection with said vaporizing tube, a plurality of leg members secured at their upper ends to said cylindrical burner member at its side walls and extending downwardly in angular position, and a pan supported below the spider-like nozzle supported by said legs and an upwardly rounded heap of loose refractory material positioned on said pan.

3. In an orchard heater of the class described, a down draft burner including a one piece casing provided with a substantially long hollow vertical cylinder provided with a spider-like opening at its lower end, a fuel inlet distributing nozzle positioned centrally in its upper end, an enclosed fuel inlet conductor positioned substantially horizontal communicating with the upper end of said distributing nozzle, a plug positioned in said casing above said distributing nozzle, an inclined vaporizing tube connected with said casing in communication with said fuel inlet conductor and in substantially close proximity to the spider-shaped open end of said burner casing whereby said vaporizing tube is preheated by said burner, and refractory material positioned in rounded relation below said spider-like opening in relatively close proximity thereto for causing the deflection of the blaze from said burner around said vaporizing tube. 40

4. In an orchard heater of the class described, a down draft burner including a one piece casing provided with a substantially long hollow vertical cylinder provided with a spider-like opening at its lower end, a fuel inlet distributing nozzle positioned centrally in its upper end, an enclosed fuel inlet conductor positioned substantially horizontal communicating with the upper end of said distributing nozzle, a plug positioned in said casing above said distributing nozzle, an inclined vaporizing tube connected with said casing in communication with said fuel inlet conductor and in substantially close proximity to the spider-shaped open end of said burner casing whereby said vaporizing tube is preheated by said burner, refractory material positioned in rounded relation below said spider-like opening in relatively close proximity thereto for causing the deflection of the blaze from said burner around said vaporizing tube, and a sludge trap integral with said vaporizing tube at its lower end adjacent said refractory material. 45 50 55 60

CHARLES W. STEWART.
